CLAIM

The ornamental design for a tractor attachment as shown and described.

DESCRIPTION

FIG. 1 is a front view of a tractor attachment in accordance with the present application.

FIG. 2 is a back view of the tractor attachment.

FIG. 3 is a left side view of the tractor attachment.

FIG. 4 is a right side view of the tractor attachment.

FIG. 5 is a top view of the tractor attachment.

FIG. 6 is a bottom view of the tractor attachment; and,
FIG. 7 is a front right perspective view of the tractor attachment.

Dashed lines represent positioning and are not claimed as part of the invention.
